UNITED STATES PATENT OFFICE.

HENRY E. PRIDMORE, OF CHICAGO, ILLINOIS, ASSIGNOR TO THE McCORMICK HARVESTING MACHINE COMPANY, OF SAME PLACE.

GRAIN-BINDER.

SPECIFICATION forming part of Letters Patent No. 292,252, dated January 22, 1884.

Application filed March 23, 1883. (No model.)

To all whom it may concern:

Be it known that I, HENRY E. PRIDMORE, of Chicago, in the county of Cook and State of Illinois, have invented certain new and useful Improvements in Grain-Binders, of which the following is a specification.

My invention relates, primarily, to a slack device for gathering in or storing up a slack length of cord from the spool and letting it out at appropriate periods in the movement of the binder-arm or revolution of the knotter.

In one of the types of binder now well known to the public, compressing arms or fingers are pivoted upon a hinged bar underlying the decking or floor of the grain-receptacle, and arranged therein so that they normally project up through said flooring and close the exit from said receptacle. Mechanism is also provided whereby the supporting-bar swings down upon its hinge at the proper time, taking with it the compressing-fingers, to permit the escape of the bound sheaf. From the lower part or shank of the compressor connection is usually made with a trip-lever fast to a rock-shaft extending longitudinally beneath the receptacle, and bearing a lifter or other suitable device, which disengages a dog or pawl from the clutch-shipper or driving-dog, and allows the latter to spring or fall into position insuring engagement, and start the machine whenever the compressor has been rocked sufficiently on its pivot to raise the trip-lever to the proper distance for the purpose. In this machine, also, a slack give-up is employed, being a rigid lever pivoted to the frame-work, at one end having an eye, through which the cord confined on either side by guides passes on its way to the binder-arm, and at the other end bearing an anti-friction roll, which rests against the effective face of a cam attached to one of the gear-wheels in the train between the trip and the binding apparatus, so that said lever shall be positively operated to draw slack from the spool and afterward yield it up at the proper time or times in the movement of the binder-arm and knotter. Such a machine, with some minor variations, I have chosen for the purpose of illustrating my invention, which latter consists in combining with the slack-lever a cam which

operates it twice for each binding operation, once to prepare a slack length for the knotter, and a second time to prepare a slack length in anticipation of the reverse movement of the binder-arm; in combining with the slack-lever a tension device resting or pressing upon the cord in its passage through the eye or eyes thereof, and arranged in such manner that the pressure will be augmented as the lever moves to draw cord from the spool; in combining with the slack-lever a tension device arranged to rest or press upon the cord in its passage through the eye or eyes thereof, and means whereby the original pressure of said device may be increased or diminished, and in the various other combinations and details of construction, hereinafter described and claimed.

In the drawings, Figure 1 is a front end elevation, partly in section, of a machine embodying my invention. Fig. 2 is a top plan view of so much thereof as is requisite to a proper explanation of the same.

A, A' are supporting-bars, usually formed of tubular metal, whereby the binding attachment is connected with the harvester.

B is the decking of the grain-chute or binding-receptacle, and C a hinged leaf or tail-board at the foot thereof. Above the decking is a guard or deflector, D, converging toward, to form a throating for the grain, and serving also to shield the holding, knotting, and cutting devices which overlie it. The binder-arm E is keyed fast to a rock-shaft, E', beneath the decking, and rises through a slot cut in the latter. A crank-arm, f, from this rock-shaft is linked by a pitman, F, with a wrist-pin, f', upon the gear and cam wheel F', fast to a shaft, F², journaled in an overhung bracket above the grain-guard, and driving ultimately the holding, knotting, and cutting devices. This gear and cam wheel is connected by intermediate pinions, G, G', with a loose pinion, H, upon the shaft H', driven constantly from the harvester, and itself driving, by cranks along its length, the packing-arms, which force the grain in practically equal wisps from the head of the decking along the chute and pack it gradually into the receptacle. Upon the constantly-driven shaft is a

clutch, I, of such construction that when tripped by the accumulation of the gavel it will engage with the loose pinion and lock it to the shaft, thereby causing it to drive the gear and cam wheel and the instrumentalities which the latter controls. A dog or pawl, I', pivoted upon the rock-shaft which carries the binder-arm, and constantly urged down by an elastic spring, i, blocks the shipper or driving-dog i', carried by the clutch, and normally holds the latter out of engagement; but when lifted against the stress of its spring releases said shipper and permits engagement.

The gear and cam wheel, by means of its cam-track f", operates, when in motion, the T-shaped lever f", pivoted by its longer arm to the frame-work or bracket-standard, having on one of its shorter arms a roller, which takes into said cam-track, and receiving in the second short arm one end of a yielding pitman, F', connected at its other end to a crank-arm from a rock-shaft, K. Another and longer crank arm from said shaft has a link-connection, k, with the supporting-bar L, which bears the compressing-fingers L', and a second link-connection with the heel-extension from the hinged leaf or tail-board, so that whenever the shaft is rocked upon its pivot by the action of the cam-track it will depress or raise the hinged supporting-bar and concurrently open or close the hinged leaf, thus leaving the exit from the grain-receptacle clear for the discharge of the bound sheaf, or closing it for the ensuing binding operation.

35. Running parallel with the binder-arm shaft, and with the rock-shaft which controls the supporting-bar for the compressor-fingers, is another rock-shaft, M, located between the two. The compressing-fingers are bolted or riveted fast to their supporting-arm, and the lever M' or trip-lever is carried up through the slot in the decking in position to intercept the grain as it is packed toward said fingers, and to recede before it as it accumulates, 40 so as to rock the tripping-shaft in the same manner as if moved by the action of the fingers of the compressor itself. At the forward or outer end this tripping-shaft has a crank-arm or lifter, m, which raises the stop-dog, and such lifter is of course furnished with the usual adjusting-screw, m', to be set up 45 against the dog and secure nicety of action.

The transmitting-pinion G', engaging with the clutch-pinion, and making two complete revolutions to every single revolution of the gear and cam wheel and concurrent binding operation, has upon its side a cam, g, of substantially the outline shown. A slack-lever, N, is pivoted to the frame-work at n, and has 55 as its heel end, or that end projecting toward the cam, a roller, n', which rests against the periphery of said cam, and travels upon it. At the other end, projecting inward toward the harvester, this slack-lever is perforated for 60 the passage of the cord, a guide, n", for said cord being placed on either side, the sill n', which underlies said end, affording convenient

means for the support of these guides. When the clutch-pinion is started in the binding operation, the ensuing motion of the intermeshing wheel forces the cam down upon the adjacent end of the slack-lever, and throws up the cord-arm of the latter as the binder-arm or needle is rising to encompass and compress the gavel, thus tightening the cord about said gavel and pulling a slack length from the spool. The knotter now starts, and the cam immediately begins to release the lever, yielding up the slack length, which is practically measured by double the distance which the lever has risen from the fixed guide-eyes n" upon the sill. This length so yielded up, it will be understood, is in the spool-strand, running through the eye of the binder-arm, other provisions—as, for example, a movable holder-frame—being employed to furnish slack concurrently from the other or old strand. As soon as the knotter ceases its revolution, and has grasped or is on the point of grasping the crossed ends of the cord, and the new end is seized by the holder, the lever again rises to gather a second slack length from the spool, and from whatever loose cord may lie between it and the binder-arm. Then, as the latter is being withdrawn beneath the decking or receiver, and the packers resume their effective action, it falls afresh to lay a sufficient quantity of free cord for the binder-arm to reach its position of rest without undue strain upon the holder, and to allow the unhindered contact of the incoming gavel with the tripping-fingers or its accumulation to a sufficient size before the tripping devices are actuated. There will thus be no danger of pulling the cord out of the holder or of breaking it, either 105 in the quick movement of the binder-arm or under pressure from the grain, urged forward forcibly by powerful packing mechanism. Tension has heretofore been applied to the cord only as it emerged from the cord-box, 110 or as it left the spool, or else upon its passage through or over some other fixed instrumentality between the source of supply and the binder-arm, and this tension has usually been continuous. The cord ran through the end of 115 the slack-lever practically uninfluenced as to tension thereby, and was always subject to the drag or strain of these extraneous instrumentalities, whether in the movement of said lever, or of the binder-arm, or of the knotter. I propose either to dispense entirely with such instrumentalities or to confine them to the office of exerting a minimum constant tension upon the cord, and to employ in connection with the slack-lever a tension acting upon the cord as 120 it passes directly therethrough, and so arranged or controlled that its action will be intensified as the lever rises. For this purpose the end of the slack-lever is broadened, so as to fill the space between the cord-guides and the sill, 125 and has ears at each side in close proximity to said guides, through which are drilled holes or eyes to receive the cord.

To the front frame-bar is bolted a casting,

O, bearing the pivot-pin *o* for the slack-lever, and inside of this arm or lever is a second arm, P, sleeved to said pin, and extending inward until it rests at its point in a space between the ears, so as to lie or press upon the cord passing from the eye in one to the eye in the other. A coiled spring, *p*, encircles the pivot-pin inside of this pressing or tension arm and bears upon a shoulder, *p'*, from the latter by one end, while the other end is made to take over or bear against one of a series of pins, *o'*, arranged in a semicircle about said plate for the purpose of permitting the stress of the spring to be varied. This spring will force the tension-arm down upon the end of the slack-lever, compressing the cord as it is pulled therethrough and retarding it. As long as the slack-lever is at rest, the pressure will be slight, or preferably nothing, so that the cord may pull through easily and freely; but whenever the cam acts upon the lever to raise it and accumulate a slack-length the tension-arm will also be raised, coiling up its spring, which will resist with constantly-increasing force, thereby causing the cord between the lever and the holder to be tightened and remain taut, though yet capable of being drawn upon so long as the lever is up. As the lever falls, the pressure will, on the contrary, gradually decrease until the normal position is again reached, when the cord will again run freely or with such slight tension as it may be deemed desirable to apply.

The cam which operates this slack-lever I form of a peculiar shape—that is, it has a cut-away portion, *g'*, in which the anti-friction roll or traveler remains at rest, and from this a sharp rise intended to depress said traveler and raise the remote or effective end of the lever when the binding mechanism starts, and after this it is laid upon a helical curve, gradually re-entering towards the axis until it returns to the cut-away portion, so that the lever may not instantly and abruptly resume its position of rest, but reach it by a gradual fall.

I do not limit myself to the peculiar shape of cam, nor to a pivoted lever, as a sliding bar may be substituted; nor do I intend to be confined to the specific combination of tension-arm with the slack-lever, or the number or arrangement of ears on the latter, considering that I am the first to apply any automatically-variable tension device directly to the cord as it passes through the eye of a slack-lever. The same construction may be advantageously employed without change, except of the time of actuation in a slack take-up, which this lever in its manner of movement, though not in its period of movement, resembles; and such use, likewise, I consider within the principle of my invention.

I claim—

1. The combination, substantially as hereinbefore set forth, with the binder-arm, and knotter, and cord-holder, of a slack device actuated twice to each binding operation, once to prepare and furnish to the knotter slack cord from the spool-strand, and the second time to prepare and yield slack to the binder-arm as it recedes from the holder. 65

2. The combination, substantially as hereinbefore set forth, with the binder-arm, knotter, and cord-holder, of a slack device intermediate between said arm and the cord box 75 or spool, and a tension device brought into effective action upon the cord at the moment said slack device is actuated to gather in or store up a slack length.

3. The combination, substantially as hereinbefore set forth, with the slack-lever, of a tension device lying or pressing upon the cord as it passes through said lever, and arranged in such manner that its pressure is increased as the lever rises. 80

4. The combination, substantially as hereinbefore set forth, of the pivoted slack-lever, the ears formed at the effective end, the cam acting upon its heel end, the independently-pivoted tension-arm resting upon the cord between said ears, and the spring acting upon said tension-arm. 90

5. The combination, substantially as hereinbefore set forth, of the pivoted slack-lever having perforated ears at its free end, the cam acting upon its heel end, the independently-pivoted tension-arm resting upon the slack-lever between said ears, the spring pressing upon said tension-arm, and means whereby the force of said spring may be adjusted. 95

6. The combination, substantially as hereinbefore set forth, of the plate bolted to the frame-work, the pivot-pin formed upon said plate, the slack-lever journaled upon said pivot-pin and formed with perforated ears at its effective end, the tension-arm resting upon the slack-lever between said ears, the spring coiled about the pivot-pin and pressing at one end against a shoulder on the tension-arm, and the series of adjusting-pins arranged upon the plate, with any one of which the second end of the spring is adapted to engage to determine its stress. 105

7. The combination, substantially as hereinbefore set forth, with the pivoted slack-lever, of the cam having the outline shown and described. 115

HENRY E. PRIDMORE.
